UNITED STATES PATENT OFFICE.

JESSE FULENWIDER AND HARRY FULENWIDER, OF SAVANNAH, GEORGIA.

ROOFING FASTENER.

Application filed January 21, 1925. Serial No. 3,799.

To all whom it may concern:

Be it known that we, JESSE FULENWIDER, and HARRY FULENWIDER, citizens of the United States, residing at Savannah, in the 5 county of Chatham and State of Georgia, have invented new and useful Improvements in Roofing Fasteners, of which the following is a specification.

This invention relates to roofing fasteners 10 and particularly to that type of device which is used for holding in place composition shingles when laid diamond-wise.

The principal object of the invention is to provide a roofing fastener which will allow 15 for thermal expansion of the shingles.

Another object of the invention is the provision of a roofing fastener having means which co-act with the edges of a shingle in the previously laid row of shingles for 20 locating the roofing fastener in proper position to receive a shingle of the row being laid.

Other objects of the invention will appear in the course of development of the following description and claims.

In the drawings:—

Figure 1 is a plan view showing a portion of the roof including overlapped shingles held in place by the device of our invention.

Figure 2 is a plan view of one of the roofing fasteners.

Figure 3 is an end elevation.

Figure 4 is a perspective view of one of the roofing fasteners.

Referring now in detail to the several figures, the numeral 1 designates shingles in a basic row. The roofing fasteners are used in pairs, rights and lefts as indicated at 20 and 3 in Figure 1 each of which fasteners consists of substantially a flat plate 4 having allocating flanges 5 and 6 struck up on two adjacent edges of said plate on one side thereof, and a trough-like flange 7 formed 45 on one of the remaining edges of said plate on the other side thereof and preferably extended longitudinally at one or both ends as indicated at 8 so as to present a relatively extensive engaging surface to the support of the shingle which is to be received by said 50 trough-like flange, thereby preventing binding and buckling of the shingle, such as takes place when relatively narrow flanges are used.

In the illustrative embodiment of our invention a pre-formed nail hole 9 is shown by

means of which the roofing fastener is secured in place, but, if desired the roofing fastener may be made without the nail hole and the latter formed by driving a nail 60 through the imperforate plate.

In the operation of using our improved roofing fastener, a pair of them, one right and one left are allocated by placing the flanges 5 and 6 against the edges which form the corners of adjacent shingles of a row already laid, this being clearly indicated in Figure 1. The trough-like flanges 7 are then in proper position to receive the corner of the overlying shingle. The roofing fasteners are secured in place by driving a nail 65 through the plate 4, corners of the adjacent shingles of the previously laid row and into the sheathing of the roof. The overlying shingle is then laid in place with the edges 70 which form its lower corner seated within the trough-like flanges 7. The latter are preferably made wider than the thickness 75 of the shingle so as to provide ample drainage and quick evaporation of moisture from 80 said trough-like flanges.

Roofing fasteners have heretofore been made with the pair of trough-like flanges formed on a single plate. These have had the drawback of causing the shingle to 85 buckle in thermal expansion by reason of its being confined within the trough-like flanges which are rigidly related and the distance between which cannot vary. In the present device the right and left trough-like flanges are formed on separate pieces and there is sufficient strain, that is to say, movement between the roofing fastener and its connection with the roof to permit the slight amount of relative elongation between 90 the right and left trough-like flanges to take care of the lateral expansion of that portion of the shingle confined between said flanges.

The lateral expansion of a shingle is 100 greater in the line of its horizontal diagonal than adjacent its lower corner, simply because its extended surface is greater in the former region. This causes a shifting in the direction of the lower edge of the shingle to the broken line position indicated at A—B in Figure 1. The single nail connection between the roofing fastener and the roof permits a slight pivotal motion of the roofing fastener so that it swings enough to 105 accommodate the change in position of the edge of the shingle under expansion, this 110

pivotal movement being compounded with the slight give between the roofing fastener and its connection with the roof above referred to. It is to be understood that the 5 actual amount of diversion in the direction of the edge of the shingle due to expansion is extremely slight and that there is always sufficient play between the allocating flanges 5 and 6 and the edges of the shingle with 10 which they co-act, to permit the roofing fastener fully to perform its function.

While we have above described what we 15 believe to be a simple and practical embodiment of the invention it is to be understood that certain changes or alterations in the construction may be resorted to if desired without departing from the spirit and scope of the invention as claimed.

Having described our invention what we 20 claim as new and desire to secure by Letters Patent, is:—

1. In a roofing fastener, a pair of plates each formed with means for supporting an

edge of a shingle, said plates being adapted for pivotal mounting upon a roof in right 25 and left juxtaposition with their shingle supporting means confronting.

2. In a roofing fastener, a pair of plates each having an angular corner, the adjacent edges forming said corner being upturned 30 on one side of said plate, another edge of each plate being formed with a trough-like shingle supporting flange upturned on the opposite side of said plate, said plates being adapted for pivotal mounting upon a roof 35 in superposed relation to a previously laid row of shingles, in right and left juxtaposition with their shingle supporting means confronting and the upturned edges in substantial contact with the adjacent corners 40 of a pair of adjacent shingles in the previously laid row.

In testimony whereof we have hereunto set our hands.

JESSE FULENWIDER.
HARRY FULENWIDER.
